UNITED STATES PATENT OFFICE.

FRANK E. BROSSY AND CARL K. FRIEDMAN, OF DETROIT, MICHIGAN.

DESIGN FOR A PEN-HOLDER.

SPECIFICATION forming part of Design No. 19,456, dated December 3, 1889.

Application filed October 28, 1889. Serial No. 328,498. Term of patent 7 years.

To all whom it may concern:

Be it known that we, FRANK E. BROSSY and CARL K. FRIEDMAN, citizens of the United States, residing at Detroit, in the county of Wayne and State of Michigan, have invented and produced a new and original Design for Pen-Holders, of which the following is a specification, reference being had to the accompanying drawings, in which our invention is shown in perspective.

The leading feature of our design consists in an ostrich-feather of any desired color, the plume portion A thereof being curled into scrolls or curls to give it an ornamental and pleasing appearance, and to the stem or quill we attach a suitable ferrule B, having a receptacle to receive the pen C. Such plumes usually are gracefully tapered and curved, so

as to form, in combination with the curls of the plume portion, a most pleasing and ornamental design for pen-holders.

What we claim as our invention is—

The design for a pen-holder herein described and shown, consisting of an ostrich feather provided with a curled plume portion, and a stem portion provided with a ferrule for the reception of the pen, substantially as described.

In testimony whereof we affix our signatures, in presence of two witnesses, this 21st day of September, 1889.

FRANK E. BROSSY.
CARL K. FRIEDMAN.
